FUEL BURNER

Elzear V. Michaud, Chicago, Ill., assignor of two-fifths to Raymond D. Schnoor, and one-fifth to Robert F. Michle, Jr., both of Chicago, Ill.

Application January 18, 1932, Serial No. 587,338

6 Claims. (Cl. 158—79)

This invention relates in general to a fuel burner and more particularly to a method of improving combustion in burners and to burning apparatus.

An important object of the invention is to provide a method of conditioning fuel as an incident to the burning thereof whereby an increased efficiency and greater heating capacity are effected. In similar apparatus provided heretofore combustion is incomplete and far below actual and inherent possibilities. This is evidenced by yellow and blue flames, smoke, carbon deposits, low heat generation, etc. In accordance with my invention the fuel, particularly liquid fuel such as oil, is conditioned to effect more perfect combustion which is evidenced by violet to invisible flame, no carbon deposit or smoke and greater heat generation per unit quantity of fuel as well as a higher degree of heat.

Another object is to provide apparatus for practically applying the method and wherein coking such as may obstruct the operation of burning is prevented. In previously provided similar apparatus preheating elements become clogged after a period of use by carbon deposits on the interior thereof rendering the apparatus inoperative. By preventing the accumulation of these deposits consistent and dependable operation of a burner is effected.

Other objects such as the economic design, adjustability and the like, will be apparent as the invention is better understood from the following description when considered in connection with the accompanying drawing forming a part hereof.

Referring to the drawing—

Figure 1 is a plan view of an apparatus embodying my invention; and

Figure 2 is a longitudinal sectional view taken substantially on line 2—2 in Figure 1.

In accordance with my invention oxygen is combined with conditioned fuel which is then expanded by exposure to heat to effect maximum combustion.

Liquid fuels such as the volatile oils when heated are expanded to vapor and then to gases in succession. The transition to vapor taking place for example in relatively heavy fuel oils at approximately 125° F. and to gas at approximately 750° F. By heating the gases beyond 750° F. they are expanded proportionately and if permitted to cool or condense in the presence of oxygen, such as in atmospheric air, oxygen will be absorbed in proportion to the extent of condensation. The ideal proportions of oxygen to fuel for substantially complete combustion has

been determined as 14 to 1 and to substantially saturate the gasified fuel with oxygen, I prefer to preheat the fuel to approximately 1200 to 1500° F. or more and then to expose the expanded gases to oxygen preferably in free air such as by discharging the fuel through a mixing tube of suitable diameter, which is determined by the volume of gas discharged, and of a length proportional to a normal velocity of the gases to permit contraction of the gas molecules to approximately 750° F. without permitting material condensation, thus effecting substantially complete saturation of the gas molecules with oxygen.

To further condition the gases or mixtures of elements they are then superheated to effect a substantial reexpansion.

One form of apparatus or burner for applying the above described method includes a jet valve 11, and a mixing tube 12 mounted in a fixture 13, a preheating element 14 and a fire pot 15.

The jet valve 11 may be any suitable device for releasing the fuel in a jet stream or the like and into the mixing tube 12, and in the present embodiment includes a body 21 in which a valve needle 22 is mounted as indicated for adjustment relative to a valve seat 23 by means of a suitable handle or wheel 24.

A sleeve 20 of frustro-conical form and having a threaded connection with the valve body 21 facilitates adjustment for controlling the relative proportions of air in accordance with the requirements of the various grades of fuel obtainable and suitable for use in the apparatus.

The mixing tube 12 is preferably a metallic tube capable of withstanding a high degree of heat and is of such a diameter as to afford a proper combustion mixture and a relatively low velocity of the combustion mixture through the tube. The tube 12 is relatively long to provide a sufficient length of time in effecting the combustion mixture to the end that an intimate combustion mixture be formed.

The fixture 13 may be any suitable bracket or fitting having a bearing portion 27 in which the tube 12 may be mounted for longitudinal adjustment and in which the valve 11 may be mounted or secured in alignment with the tube 12 as indicated.

The valve 11 may be rigidly secured in the fixture 13 in any suitable manner and the tube 12 may be secured in adjusted relationship with respect to the valve 11 by means of a set screw 28 or the like.

The preheating element 14 is preferably a tubular conductor arranged in or about the fire pot 15.

15 or formed spirally about the fire pot end of the tube 12 as shown. In the present embodiment this element is formed of a material capable of withstanding extreme heat wrapped to 5 form a close wound internal helical coil 31 and a close wound external helical coil 32 closely nested on the internal coil. The coils 31 and 32 being connected or formed of a continuous tube and connected to an extended portion 33 of the valve 10 body 21 through connecting tubes 34 and 35 integral therewith and suitably connected to the portion 33 as indicated.

In accordance with my invention the tubes 34 and 35 are interconnected to form a closed fuel 15 circuit through the coils 31 and 32 and a connecting or by-pass channel 36 formed in the extended portion 33 of the valve body 21 or the like.

Fuel is supplied to the closed circuit under 20 pressure from a tank 37 or other source of supply through a tube 38 suitably connected to the valve portion 33 and delivered to the restricted outlet jet of the valve 21 through an extended portion 39 of the channel 36 as indicated.

25 Means is provided for insuring a unidirectional flow through the by-pass channel 36 in the direction from the outlet side of the preheating element 14 to the inlet side thereof, and, as shown, this means consists of check valve comprising an upwardly facing valve seat 41 formed in the channel 36 and a check ball 42 engaging downwardly on the seat under the influence of gravity.

A pin 43 formed on an adjustable stop plug 44 35 extends into the channel 36 to limit upward or opening movement of the ball 42.

The burner apparatus may be attached to a fire box 45 or to other apparatus by means of a mounting bracket 46 suitably secured to the fire 40 box as indicated having a bearing portion 47 in which the burner apparatus may be longitudinally adjusted and rigidly secured in adjusted relationship by means of a set screw 48 or the like.

The fire pot 15 is preferably formed of lava 45 or similar material capable of resisting at least 3500° F. of heat. Essentially the fire pot 15 is a hood covering the combustion end of the mixing tube 12 and the coils 31 and 32 with one or more openings such as an opening 51 of sufficient total 50 capacity to permit maximum heat radiation while retaining sufficient heat in the fire pot 15 to promote maximum combustion. The relative proportions being determined by the normal capacity of the burner apparatus.

55 The fire pot 15 may be mounted in the mounting bracket 46 as indicated or arranged in the fire box 45 in any suitable manner.

The burner is started by opening the valve 11 and at least partially filling a sump 55 formed 60 in the fixture 13, igniting the fuel in the sump to start generation of gas with the valve 11 closed. After a brief period vaporizing is started, at which time the valve 11 may then be opened and while combustion is relatively low with vaporized fuel 65 the flame rapidly settles down to relatively complete combustion as sufficient heat is accumulated to gasify and expand the gasified fuel. When the burner is functioning normally the combustion is sustained in the fire pot 15 at the inner or 70 outlet end of the mixing tube 12, at which end the preheating element 14 is disposed.

Assuming the burner to be functioning normally, liquid fuel under pressure in the tank 37 passes from the tank through the tube 38 into 75 the channel 36 above the check ball 42 engaged

on the seat 41, then into the tube 34, and then into the inner coil 31 of the preheating element 14.

In the gasification of the fuel in the preheating or gasifying element 14, sudden momentary 5 expansions take place in this element and, due to the inertia of the liquid fuel in the fuel feed line and the inner coil 31, these sudden expansions cause momentary excess pressure on the gasified fuel in the outer coil 32 outlet tube 35, 10 the extended portion 39 of the channel 36 below the valve seat 41 and in the valve 21, that is to say, at the outlet side of the element 14.

When such an expansion takes place, the resulting excess pressure at the outlet side of the 15 element 14 causes the lifting of the check ball 42 from its seat 41 and a flow of gas into the fuel line which ceases and permits the check ball 42 to again engage the seat 41 upon pressure equilibrium being again established between the inlet 20 and outlet sides of the element 14, the check ball 42 and its seat preventing a flow through the by-pass channel 36 from the inlet side of the element 14 to the outlet side thereof.

As a result of this action, not only is excess 25 pressure difference at the outlet jet, which results in the burner surging, prevented, but the by-pass, entering the fuel line, serves to prevent coking in and consequent clogging of the element 14, at least to such an extent, as proven by extended test, that the element 14 will function 30 indefinitely. In addition a portion of the bypassed gas enters the tank 37 through the tube 38 as a fixed gas and maintains the pressure in the tank despite the flow of fuel therefrom. 35

The exact functioning of the by-pass in the prevention of coking in the element 14 is not definitely known to me, but it is my theory that the by-passed gas, entering the system in circulation 40 controlling relation with the element 14 and opposing backward movement of the liquid fuel therefrom, maintains a substantially constant and violent circulation in the element 14 and thus prevents the anchoring of carbon therein. At any rate, in operation the pulsations through 45 the by-pass occur at substantially uniform periods of short duration.

The constant circulation in the member 14, as effected by the by-pass, serves to prevent overheating of this element. The mixing tube is 50 relatively long for the proper mixture of the fuel gas issuing from the jet of the valve 21 with a supporter of combustion, such as air as shown, and by reason of the fact that the inner coil 31 is connected with the fuel source and thus remains 55 relatively cool, this coil tends to prevent overheating of the outlet end of the mixing tube and consequent back firing in the mixing tube.

It is thought that the invention and many of its attendant advantages will be understood from 60 the foregoing description, and it will be apparent that various changes may be made in the form, construction, and arrangement of the parts without departing from the spirit and scope of the invention, or sacrificing all of its material advantages, the form hereinbefore described 65 being merely a preferred embodiment thereof.

I claim:

1. In a device of the character described the combination of a conduit having a conditioning 70 portion one end of which is connected with a liquid supply under pressure and the other end of which is provided with a restricted outlet, an additional conduit connecting said conduit at the outlet and inlet ends of said portion to pro- 75

vide a flow from the outlet end to the inlet end of said portion upon excess pressure occurring at said outlet end, and means for preventing a flow of liquid through said additional conduit to said outlet end.

2. In a device of the character described the combination of a conduit having a conditioning portion one end of which is connected with a liquid supply under pressure and the other end 10 of which is provided with a restricted outlet, a by-pass conduit connecting said conduit at the outlet and inlet ends of said portion to provide a flow from the outlet end to the inlet end of said portion upon excess pressure occurring at said 15 outlet end, and a check valve for preventing a flow through said by-pass conduit to said outlet end.

3. In a liquid fuel system the combination with a pressure tank, of a conduit having a conditioning portion one end of which is connected with said tank for the supply of liquid therefrom and the other end of which is provided with a restricted outlet, and additional conduit connecting said conduit at the outlet and inlet ends of 20 said portion to provide a flow from the outlet end to the inlet end of said portion upon excess pressure occurring at said outlet end, and means for preventing a flow of liquid through said additional conduit to said outlet end.

4. In a liquid fuel system the combination with a pressure tank, of a conduit having a conditioning portion one end of which is connected with said tank for the supply of liquid therefrom and the other end of which is provided with a restricted outlet, a by-pass conduit connecting said conduit at the outlet and inlet ends of said portion to provide a flow from the outlet end to the inlet end of said portion upon excess pressure occurring at said outlet end, and a check 35 valve associated with said by-pass conduit for preventing a flow through said by-pass conduit to said outlet end.

5. In a liquid fuel burner the combination of

a burner tube, a conduit having a conditioning portion comprising nested inner and outer helical coils surrounding said burner tube in the region of its outlet end and having the ends thereof corresponding with the outlet end of the burner tube connected, the end of said inner coil which is remote from the outlet end of said burner tube being connected with a source of liquid fuel supply, an outlet jet device connected with the end of the outer coil which is remote from the outlet end of the burner tube and said jet device being disposed remote from the outlet end of the burner tube to project fuel through the burner tube toward the outlet end thereof, and means responsive to excess pressure at the outlet jet end of 15 the outer coil and effective upon the liquid in the conduit between the fuel inlet end of the inner coil and said source of supply to oppose backward movement of the liquid from the inner coil.

6. In a liquid fuel burner the combination of a burner tube, a conduit having a conditioning portion comprising closely nested inner and outer helical coils surrounding said burner tube in the region of its outlet end and having the ends thereof corresponding with the outlet end of the burner tube connected, the end of said inner coil which is remote from the outlet end of said burner tube being connected with a source of liquid fuel supply, an outlet jet device connected 20 with the end of the outer coil which is remote from the outlet end of the burner tube and said jet device being disposed remote from the outlet end of the burner tube to project fuel through the burner tube toward the outlet end thereof, a by-pass conduit connecting the outlet jet end of the outer coil with the fuel inlet end of the inner coil, and a check valve associated with said by-pass conduit for preventing a flow through said by-pass conduit to the outlet jet end of said outer 25 coil.

ELZEAR V. MICHAUD.
